Specification for Design.

Patented Mar. 15, 1921.

Application filed January 2, 1920. Serial No. 349,046. Term of patent 14 years.

To all whom it may concern:

Be it known that I, CULLEN C. EVANS, a citizen of the United States, residing at Los Angeles, in the county of Los Angeles and State of California, have invented a new, original, and ornamental Design for Wrenches, of which the following is a specification, reference being had to the accompanying drawing, forming a part thereof.

In the drawings,

Figure 1 is a plan view of my wrench.

Fig. 2 is a side elevation.

Fig. 3 is a vertical cross section taken on the line 3—3 of Fig. 1.

Fig. 4 is an end view looking from the left of the wrench shown in Fig. 2.

I claim:

The ornamental design for a wrench as shown.
